his ATTORNEY.

UNITED STATES PATENT OFFICE.

JOHN R. RUSSELL, OF STERLING, ILLINOIS.

QUILTING FRAME.

Application filed January 11, 1926. Serial No. 80,508.

My invention has reference to quilting frames, of that class which is used in connection with a sewing machine, for supporting the work while the quilting is being done by the machine. One of the purposes thereof is to provide a supporting frame for the device, possessing a maximum of strength, and capable of various adjustments, to conform the same to the requirements of the movable frame.

Another feature thereof consists in the support of the movable frame so that it will be capable of the greatest amount of flexibility, to permit the same to respond promptly to the movements of the operator. Coupled therewith are certain adjustable features which will enable the frame to be positioned most suitably for its work.

Another object of the invention consists in the provision of a novel frame for the support of the quilt which is being operated upon, and additional supporting members to be used with some classes of work. The quilts are usually formed of two covers and a filling of cotton batting or similar material, and in some cases a heavier filler consisting of a heavy layer of wool, enclosed in a cheesecloth casing, which is difficult to handle, and requires special means of support. A special supporting device is supplied for this heavier material, with means for adjustment thereof so that the same may be made to conform to material of different weights.

The above named, and other features and advantages of the invention will more fully appear from the following specification, taken in connection with the accompanying drawings, in which;

Fig. 1 shows the complete device, in side elevation.

Fig. 2 is a plan view of the quilting frame.

Fig. 3 is an end view of the quilting frame.

Fig. 4 is a plan view of one end of the bar 18.

Fig. 5 is a detail of the bolt 35 and appurtenant parts.

The reference number 1 indicates the ceiling of a room, to which is secured a framework consisting of a bar 2, supported at its ends by tubular members 3, and in the center by a support 4. The supports 3 are secured to the ceiling by means of footings 3^a, and the support 4 by a similar footing 4^a. Slidable in the supports 3 are rods 5, said supports being provided with a plurality of openings 6, through one of which is passed

a pin 7, into similar openings in the rods. The lower ends of the rods 5 are perforated, to receive a cable 8, the ends of which are connected with turnbuckles 9, which are in turn connected with wires 10, attached at their upper ends to the posts 3, near their upper ends. Said wires pass round sheaves 11 in the outer ends of arms 12, supported from the posts 3. By this means a truss support is formed for the cable 8, and by operation of the turnbuckles the cable can be maintained in a taut condition. If one end of the cable 8 is higher than the other the proper adjustment can be made by means of the openings 6 in the post 3, the pin being removed to permit movement of the rod 5, and then replaced in the proper opening. In the same way an adjustment of the entire cable with reference to the floor of a room may be made, both of the rods 5 being raised or lowered, as desired. In lowering the cable the turnbuckles 9 are first loosened, and again tightened after the adjustment has been made.

Supported from the cable 8 is a bar 14, by means of grooved wheels 15, from which the bar is suspended. Depending centrally from said bar is a pendant 16, in the lower end of which is a ring 17, from which is suspended a bar 18, by means of wires 19 connected with the ring, and shackles 20 connected with said bar near its ends, the wires and shackles being united by straps 21, capable of adjustment in length. At their upper ends the wires 19 are provided with spring coils 22, giving a yieldable support to the parts below the same. The shackles 20 are held in place by bolts 23 in the ends thereof, passing through slots 24 in the ends of the bar 18. The ends of the bolts are fitted with thumb-nuts 25, by means of which the ends of the shackles can be brought into close engagement with the sides of the bar, to hold the shackles from movement. As a further safeguard a series of openings 26 is provided in each end of the bar 18, projected through the slots 24, to receive pins 27. By adjustment of the bolts 23 in said slots the height of the bar 18 with relation to the cable 8 may be varied. To move the bolts the pins 27 are first withdrawn, and after the adjustment is made, are replaced alongside the bolts, to prevent their further movement inwardly.

In the ends of the bar 18 are fixed hangers 29, projected downwardly, and having forked ends 30, in which are supported end pieces

31, between which are held rollers 32, 33, and 34, so as to be independently rotatable. The end-pieces and rollers comprise a frame of well known construction, for the support of the materials of a quilt while being operated upon. The ends of the forks 30 are formed into eyes through which pass bolts 35, which also pass through slots 36 in the end-pieces, the bolts being provided on their inner ends with thumb-nuts 37, by means of which the ends of the forks can be drawn into close engagement with the side faces of the end pieces. The bolts 35 are preferably provided with rollers as shown at 38 in Fig. 5, giving greater freedom to the movements of the bolts in adjusting the positions thereof in the slots 36. By changing the positions of the bolts in said slots the quilting frame can be shifted to one side or other of its supports, to balance the load supported on said frame. At one end the rollers 32, 33, and 34 are provided with pins which are held in the ends of slots 39 in one of the end pieces 31, and the opposite ends of said rollers are fitted with collars 40, having openings to receive the ends of hooks 41, whereby the rollers may be held from rotation. This is a common construction in devices of this kind. By releasing the hooks the work on the rollers can be turned into new positions as the work progresses, and to remove the work the pins in the ends of the rollers are slipped from the slots 39. The roller 34 is generally made use of in operating the frame, and the pin in the end thereof is held from accidental release by means of a pin 34^a, projected downwardly through the end of the slot 39. By removing this end of the roller 34 the end-piece 31 adjacent thereto can be positioned with the foot of a sewing machine on the inner side thereof, ready for operation.

A pair of arms 42 is supported at one end by means of the bent ends of said arms projected through the slots 36, and provided on their threaded ends with thumb-nuts 43. Washers 44 are interposed between the arms 42 and the outer faces of the end-pieces 31, and by tightening the thumb-nuts the ends of said arms are held from movement in the slots 36. At the opposite ends of the arms 42 is supported a bar 45, at a distance beyond the roller 32, upon which any material may be supported which cannot be readily held on

the main frame. The ends of the bar 45 are further upheld by means of a pair of straps 46, connected with the ends of said bar, and passing through loops 47 in the ends of the bar 18. By means of buckles 48 on said straps the straps may be lengthened or shortened to conform to the position of the bar 45. On the sides of the end pieces 31 are hooks 49, which further support the arms 42. Wool filler or other heavy material which is to be used in the making of a quilt is supported by the roller 32 and bar 45. In case of an increased amount of the material being used, the ends of the arms 42 can be loosened and moved in the slots 36 to give a wider spacing between the roller 32 and bar 45, the straps 46 being correspondingly lengthened. The arms are then again secured in place.

In case of any tendency of the cable 8 to sag it can be quickly tightened by means of the turn-buckles 9, and said cable, with the carrier 14, rollingly supported at two spaced points, provides a trolley suspension for the swinging frame, which responds promptly to any impulse given to said frame. The manner of support of the swinging frame from the bar 14 also permits said frame to be turned in any direction to accommodate the same to the pattern that is being formed on the work carried thereby. This includes a yieldable action resulting from the springs 22. The adjustment features at the ends of the bar 18 also enable the height of the quilting frame to be changed so as to conform the same to the height of the machine by means of which the quilting is being done, without the necessity of disturbing the overhead supports.

What I claim, and desire to secure by Letters Patent, is:

A quilting frame comprising a supporting bar, a pair of end pieces longitudinally slotted, connections between said bar and end pieces capable of adjustment in said slots, a set of rollers supported by said end pieces, an auxiliary bar and connections between said bar and frame, also capable of adjustment in said slots, and flexible means of connection between said first named bar and said auxiliary bar capable of holding said auxiliary bar in adjusted positions.

In testimony whereof I affix my signature.
JOHN R. RUSSELL.
